UNITED STATES PATENT OFFICE.

WILLIAM A. WALKER, OF ROME, NEW YORK.

STEAM-ENGINE VALVE.

SPECIFICATION forming part of Letters Patent No. 395,725, dated January 8, 1889.

Application filed June 27, 1887. Serial No. 242,591. (No model.)

To all whom it may concern:

Be it known that I, WILLIAM A. WALKER, of the city of Rome, in the county of Oneida and State of New York, have invented certain new and useful Improvements in Steam-Engine Valves; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to an improvement in steam-engines; and it consists in the mechanism and construction hereinafter set forth, described, and claimed.

In the drawings presented, Figure 1 represents a plan view of my engine. Fig. 2 represents a side elevation of the same. Fig. 3 represents a transverse section of the cylinder and steam-chest on line A A of Fig. 4. Fig. 4 represents a longitudinal section of the cylinder and steam-chest on line B B of Fig. 5. Fig. 5 represents an end elevation of one of the steam-valves, and Figs. 6 and 7 represent side elevations of the same. Fig. 8 represents a valve having the steam-ports therein spiral or at an angle to the plane of its rotation. Fig. 9 represents a side elevation of one of the devices employed for reversing the engine.

Like numerals of reference refer to like parts in the several figures presented.

Having described my invention in relation to the drawings, I will now proceed to describe its construction and operation.

1, Figs. 1 and 2, represents the frame or bed of the engine, to which is attached by any well-known method the guides, the cylinder and steam-chest, the main-shaft bearing, and such other parts as ordinarily enter into the construction of a steam-engine. The main point of difference between my invention and the ordinary steam-engine is found in the steam-valves and their appendages and their method of operation.

2, Figs. 1, 2, 3, and 4, represents the cylinder of my engine, which contains an ordinary piston and rod.

3, Figs. 1, 2, 3, and 4, represents the steam-chest, which is attached to or made a part of

the steam-cylinder and contains the valves, the purpose of which is to permit the ingress and egress of steam to and from the cylinder. 55

4, Fig. 4, represent the ports or passages that form a communication between a steam-chest and the cylinder.

5, Fig. 4, represent the exhaust-ports, which, in connection with the steam-ports 60 4 and the valves, establish communication between the interior of the steam-cylinder and the exhaust-chamber 6, Figs. 3 and 4. This exhaust-chamber has connected with it and opening from it an ordinary exhaust-pipe, 7, Figs. 2, 3, and 4. The steam-chest 3 is properly bored on its interior to admit of the introduction of the valves 8, which are fitted substantially steam-tight therein. These valves are keyed or otherwise rigidly 70 fastened to the valve rod or shaft 9, Figs. 1, 2, 3, 4, and 9. This rod or shaft 9 receives a continuous rotary movement from the main shaft of the engine through the medium of the beveled miter-gears 10, Figs. 1 and 2. As 75 it is often desirable to reverse the motion of the engine, I provide means for so doing by the use of the devices hereinafter described. Figs. 1 and 2 show a system of beveled gearing for accomplishing this purpose. The two 80 gears 10 10, that are shown as located on the main shaft 20 of the engine, are rigidly attached to a sliding sleeve that is fitted over and upon the main shaft of the engine. This sleeve and its attached gears are connected 85 with the main shaft by spline, key, feather, or any other well-known mechanical device (not shown) in such manner as to rotate in combination therewith and still be free to move longitudinally thereon. When the 90 sleeve and gears are in the position shown in full lines in Fig. 1, the valve-shaft 9 is rotated in a certain direction and the motion of the engine is in a certain direction. When the sleeve and gears are moved into the position shown in 95 dotted lines in Fig. 1, the valve-shaft 9 is rotated in a contrary direction from that assumed in the first instance, and the motion of the engine is reversed. I also accomplish the same result by the use of the device shown in 100 Fig. 9. This device is not shown in connection with other parts of the engine; but its operation will be readily understood from the description by one skilled in the art to which

it pertains. In this construction I use only two gear-wheels instead of three, as shown in Fig. 1.

Reference to Fig. 9 will show that the valve-shaft 9 is severed or cut in two at 11. The sleeve 12 is bored to an appropriate size and is slipped over the severed portions of the shaft, as shown. This sleeve has a spiral cut or slot extending from its periphery to its inner bore and encircling substantially one-half the sleeve, as shown at 13, Fig. 9. This spiral groove or slot furnishes a guide for the pin 14, which is rigidly attached to or a part of the shaft 9. The sleeve also has, located in such a position as to not interfere with the spiral groove or slot, a longitudinal slot, 15, (shown by dotted lines,) which is parallel with the axis of the sleeve and extends through the walls of the same from its periphery to its central bore. This slot 15 furnishes a guide for the pin 16, which is rigidly attached to or a part of the shaft 9. Assuming that the lower end of the shaft 9 is held against rotary movement, it follows that when the sleeve is moved into the position shown in dotted lines in Fig. 9 engagement of the pin 14 by the walls of the spiral slot 13 will cause that part of shaft 9 above the separation or cut 11 to partially rotate in the direction indicated by the arrow. Applying this mechanism to the valve-shaft of my engine and operating it as described will reverse the position of the valve-shaft and valves in relation to the piston movement, and consequently reverse the motion of the engine.

The valves of my engine are shown in end and side elevation in Figs. 5, 6, 7, and 8, and may be described as follows: They consist, primarily, of an outer rim or shell connected with a central hub by radial spokes or arms, substantially as shown. Extending entirely through the metal forming the rim or outside of the valve is the transverse slot or steam-induction port, as shown at 17, Figs. 3, 5, and 6. At a point approximately opposite the slot 17, the exact position of which is not intended to be shown in the drawings, is the "eduction-port," (so called,) which is a depression or pocket formed in the material of the valve-rim and not extending entirely through the same, as shown at 18, Figs. 3, 5, and 7. The function of the pocket 18 is to, at proper points in the rotation of the valve and the stroke of the engine, establish communication between the steam or induction ports 4 and 5 and the exhaust or eduction ports 5, Fig. 4, and allow the exhaust-steam to pass out through the ports 4, 4, the valve-pocket 18, and the exhaust-ports 5, 5 into the exhaust-chamber 6, and thence out through pipe 7.

It will be noticed by reference to Figs. 3 and 4 that the steam-valves 8 are so located and placed in the steam-chest that they are entirely encompassed or surrounded by the steam therein, and are substantially what is technically known as "balanced" valves.

The operation of my improved engine is substantially as follows: Steam is admitted to the

interior of the steam-chest (in the construction shown through pipe 19, Figs. 1 and 2) and fills the same. Entering the cylinder through the proper port it exerts its power upon the piston and moves the same longitudinally in the cylinder. This movement of the piston is, by means of the usual mechanism, transmitted to the crank, which rotates the main shaft 20 of the engine. The rotary movement of the main shaft is, by the mechanism hereinbefore described, transmitted to the valve-shaft 9 and the engine set in motion. As the valve-shaft and its attached valves rotate, the steam-port 7 in the valve is brought into coincidence with the steam-port 4 of the cylinder, and steam is admitted into the interior of the cylinder. As the rotation of the valve continues, the port 7 passes port 4, and steam is cut off from the cylinder. The rotation of the valve continuing, the pocket 18 therein (which in longitudinal length is at least equal to the width of the ports 4 and 5 and their separating-bridge, as shown in Fig. 4) is brought into connection with ports 4 and 5 of the cylinder and establishes communication between the same and exhaust-chamber 6 and allows the steam to exhaust from the cylinder. This cycle of operations continues so long as the engine is in motion.

While my engine admits of the use of the independent governing mechanism, known as a "throttling" governor, there are some objections to the use of the same, and I therefore make use of the governing device hereinbefore described. Reference to Figs. 1 and 2 shows a sleeve, 21, located on the valve-shaft 9. The valve-shaft is cut or severed at or near the longitudinal center of the sleeve. (Cut not shown.) That portion of the valve-shaft 9 nearest the beveled gears is rigidly keyed or otherwise attached to the sleeve. That portion of the shaft 9 extending from the center of the sleeve to and into the valve-chamber is "splined" or "feathered" to the sleeve in such manner as to rotate therewith and still be free to move longitudinally within certain limits. Rigidly attached to that portion of shaft 9 last described and rotating therewith is a circumferentially-grooved collar, 22, Figs. 1 and 2. This collar is engaged by the fork or bifurcated end of the bell-crank 23, which is fulcrumed at 24 upon a projecting arm, 25, which may be a portion of the steam-chest head. The outer end of the horizontal arm of the bell-crank is engaged with an ordinary ball-governor, 26, in any of the various well-known ways. The governor is properly mounted upon the engine and connected therewith to be rotated in any appropriate manner.

Reference to Fig. 4 will show that the valves 8 are so located upon the shaft 9 that a certain amount of space exists between them (the valves) and the heads of the steam-chest, as shown at 27. It is also evident that were the shaft 9 and its attached valves 8 moved in either direction longitudinally from the

normal position shown in the drawings the effect would be to diminish the area of the induction-port opening, and consequently diminish the amount of steam admitted to the 5 cylinder. Taking this fact into account, I use the governor as a means for moving the valves and valve-shaft longitudinally in either direction, which I do by means of the intervening mechanism, as hereinbefore described.

10 Fig. 8 shows a side elevation of a valve that differs from Figs. 5, 6, and 7 only in having steam-port 28 therein, and corresponding to 17, Figs. 3, 5, and 6, cut spirally across and through its rim or shell.

15 I am aware that engines have been previously constructed embodying some of the features embraced in my engine; but I am not aware that a valve similar in construction to that shown has ever before been used.

20 It being evident that the operation of my valve could be accomplished by other means than those specifically described and shown, I do not intend to limit the broad scope or intent of my construction to the precise specific configuration, conformation, or combination of parts herein set forth and described.

25 While I have referred in this specification to my engine as a "steam-engine," I reserve the right to apply it to any purpose to 30 which it may be found to be adapted and to employ any force—such as gas, water, &c.—as a motive agent.

What I claim as new, and desire to secure by Letters Patent, is—

35 1. The combination, within a steam-chamber, of a circular seat having two ports therein and a cylindrical shell having a slot or port through the shell adapted to register with one of the ports in the seat and having a pocket 40 or recess upon the external cylindrical surface of the shell adapted to cover both ports in the seat and establish communication between them, one or more shells being mounted on a shaft within the chamber, so as to admit 45 of a lateral movement of the shell upon the seat within the chamber.

2. In a rotary valve for a motor, the combination of a curved valve-seat located in a steam-chamber, the seat being provided with 50 an inlet and exhaust ports for each end of the cylinder, a cylindrical shell mounted upon a shaft within a chamber, rotating in the

curved seat, covering the ports, and provided with slotted openings through the shell adapted to register with the inlet-ports in the seat 55 with each revolution of the shell, and recesses or pockets upon the external cylindrical surface of the shell, each pocket being adapted to cover the exhaust and inlet ports at each end of the cylinder and establish communication between them with each revolution of the valve, the shell being longitudinally adjustable in the seat, whereby the slotted openings of the shell are adjusted to a position not to or only partially to register with the 60 inlet-ports.

3. The combination, with a rotary valve of a motor having a cylindrical shell mounted on a shaft covering inlet and exhaust ports for each end of the cylinder in a circular seat 70 and the shell provided with slotted openings for establishing communication between the inlet-ports and the interior of the cylindrical shell and pocket upon the exterior cylindrical surface of the shell for establishing communication between the inlet and exhaust ports, of a governor connected with the shell for adjusting it longitudinally in the seat.

4. A steam-chamber having a circular seat 80 having ports therein, and a rotary valve consisting of a cylindrical shell having a slot or port through the shell adapted to register with one of the ports in the seat and having a pocket or recess upon the external cylindrical surface of the shell adapted to simultaneously 85 cover two of the ports in the seat and establish communication between them, one or more shells being mounted upon a shaft within the chamber, so as to revolve and also admit of a lateral movement of the shell upon the 90 seat, the shaft being in sections and one of the sections provided with a movable sleeve revolving with and longitudinally adjustable upon the section of the shaft, the sleeve having a spiral slot and the other section of the 95 shaft entering the sleeve and provided with a projection engaging the sleeve within the slot.

In witness whereof I have affixed my signature in presence of two witnesses.

WILLIAM A. WALKER.
